Primary Examiner — Marissa J Cash(74) *Attorney, Agent, or Firm* — Johnson, Marcou, Isaacs & Nix, LLC(57) **CLAIM**

I claim the ornamental design for an aircraft radome, as shown and described.

DESCRIPTION

FIG. 1 is a side view of the aircraft radome, a side view of the reverse side is a mirror image of the illustrated side; FIG. 2 is a bottom view of the aircraft radome; and, FIG. 3 is a front view of the aircraft radome; and, FIG. 4 is a back view of the aircraft radome. The broken lines shown in the drawings illustrate portions of the aircraft that do not form part of the claimed design.
